UNITED STATES PATENT OFFICE.

LOUIS J. GROVES, OF NEW YORK, N. Y.

DUPLEX STRAINER.

Application filed October 12, 1920, Serial No. 416,387. Renewed August 13, 1924.

To all whom it may concern:

Be it known that I, LOUIS J. GROVES, a citizen of the United States, residing in New York, in the county of New York and 5 State of New York, have invented certain new and useful Improvements in Duplex Strainers, of which the following is a specification.

My present invention relates to improvements in duplex strainers, an apparatus for removing sediment and impurities in general from fluids or liquids, such as fuel oil, boiler feed-water, etc., and which, when one strainer basket becomes clogged or 10 fouled, permits the putting into service of the other clean strainer basket, and the removal for cleaning of the clogged strainer basket, without interrupting the flow of fluid through the pipe line, being useful in continuous processes involving straining of fluid where it is impracticable, inconvenient, or costly to interrupt the flow of fluid through the pipe.

My invention resides more particularly 15 in the valve, and valve control or actuating mechanism of the strainer. Heretofore, in devices of this type, there were required to control the valves two or more threaded operative members, one for the 20 inlet valves and one for the outlet valves; whereas, I, in this invention, control both the inlet and outlet valves by a single threaded operative member, and control them substantially simultaneously. This 25 simplifies and facilitates control and operation of the valves, and thereby the use of the strainer in general. For, inasmuch as each threaded operative member requires a hand wheel or other suitable actuating 30 means, and I, in this invention, having only one threaded operative member, and, therefore, only one hand wheel or actuating means, and all previous devices of this 35 type having two or more threaded operative members, and, therefore, two or more hand wheels or other actuating means, and, as the simplicity of handling one hand wheel as compared with the handling of two or more simultaneously is evident, the 40 improvements embodied in my invention 45 will be apparent.

Again, heretofore, in devices of this type, much trouble has been experienced by the 45 wearing of the valve and valve seats, caused 50 by the valves sliding on their seats under

pressure. Another feature of this invention consists of eliminating this wear by means of inclined surfaces, to be described more fully in detail later, whereby, in opening the inlet and outlet ports of either of 60 the strainer chambers the single common inlet valve and the outlet valve with which it is engaged are caused to be forced in a direction away from each other and from their seats, after which the pressure being 65 equalized on both sides of the valves, the common inlet valve, which in the device is the only sliding valve, can travel forward without wearing or grinding its seat.

These and other features and capabilities of my invention will be disclosed in 70 the course of the following description of the invention.

In the accompanying drawings which 75 show one embodiment of my invention and which form part of this specification, Figure 1, is a sectional plan view taken through the middle of the valve mechanism.

Figure 2, is a vertical section on the line 2-2 of Fig. 1, looking in the direction of 80 the section line arrow.

Figure 3, is a detail sectional view of link connected abutment members comprised in the valve mechanism.

Figure 4, is an exterior view of the single 85 or common inlet valve showing the wedge face thereof, and showing a portion of the threaded single member for operating said valve.

Similar reference characters denote similar 90 parts throughout the several views.

My invention comprises in its main elements or parts the strainer body 10 containing the strainer baskets 11, the single or common inlet valve generally denoted 95 by 12, the outlet valves generally denoted by 13, and the single threaded valve actuating member 14.

The strainer body 10 is a casting having formed therein the strainer chambers 15 100 which preferably are cylindrical. The strainer body 10 is provided with inlet ports 16, an inlet port for each strainer chamber, these inlet ports being controlled alternately by the single common inlet valve 12, and outlet ports 17, an outlet port for each strainer, each one of these outlet ports being controlled by separate outlet valves 13. Communication is had between the inlet 105 ports 16 and the strainer or filter chambers 110

15 by passageways 18, and between the strainer or filter chambers 15 and the outlet ports 17 by passageways 19, these passageways being formed by partitions 20, 21, and 22. 5 Valve caps or housings 23 and 24 are provided for the inlet and outlet ends respectively of the strainer body 10. The valve cap or housing 23 forms the fluid inlet chamber 25 and the valve cap or housing 24 forms the fluid outlet chamber 26, the cap or housing 23 being secured to the inlet end of the strainer body 10 in a fluid tight manner as by the bolts 27, and the cap or housing 24 being secured to 10 the outlet end of the strainer body 10 in a fluid tight manner, as by the bolts 28, the cap or housing 23 having a suitable attachment extension 29, and an inlet delivery port 30, and the cap or housing 24 having a suitable attachment extension 31 and an outlet delivery 32.

The strainers 11 are of cylindrical basket form, that is, they are intended to conform to the strainer chambers 15, and are of suitable material for straining fluid therethrough. Each of the strainer baskets 11 has at its mouth an annular flange member 33 with an annular disk or ring plate 34 thereon, which disk or ring plate 34 forms 25 a flange extending beyond the member 33 and may be integral with the member 33 or suitably secured thereto, the purpose of the annular disk or ring plate 34 being to engage a ledge 35 formed on the interior of the 30 strainer chambers 15 for supporting the strainer basket in the strainer chamber, with space of the strainer chamber around the circumference of the strainer. A bail 36, either integral with or suitably secured to 35 the strainer, is provided for each of the strainer baskets 11, the bails 36 extending somewhat above the line of the open ends of the strainer chambers for the purpose later stated. A cap, or cover, such as 37 is provided for the open end of each strainer chamber, the caps 37 being removably secured to the strainer body 10 by bolts 38 passing through the caps. Each cap has a gasket or washer 39 of suitable material for 40 preventing leakage from the strainer chamber. Each cap 37 is so constructed that the under side of the cap will engage or press upon the end of the bail 36 when the cap 37 is in closing position and the strainer basket is in operative condition in the strainer chamber; the intention being that the annular disk or ring plate 34 will be forced down into close contact or engagement with the upper face of the ledge 35 of the strainer chamber, thus providing fluid tight connection between these members, and permitting no liquid, other than the liquid which passes through the strainer basket and is strained or purified, to pass out through the outlet 45 port.

The outlet valves generally denoted by 13 each comprise the valve member 40, Fig. 2, which is a plate having an extended edge portion 41 and an extended under portion 42, which provides the valve face for engaging the outer surface of the outlet end of the strainer body 10, such face and surface being ground or otherwise prepared to afford fluid tight engagement therebetween. The extended edge portion 41 has apertures 43 therethrough.

The strainer body 10 is bored straight through from the outlet end as at 44 to the inlet end as at 45, the borings at the inlet end being enlarged at 46 for the purpose later 80 stated.

Each of the valve members 40 is provided with valve stems 47, these valve stems extending freely through the apertures 43 and through the borings 44-45 into 85 the inlet chamber 25.

The valve stems 47 are provided with collars 48, pinned or otherwise suitably secured thereto, and located in the space between the extended edge portion 41 of the valve members and the outer surface of the outlet end of the strainer body 10. Spherical seated washers 49, retained by the collars 50, encircle the valve stems 47 and seat upon the extended edge portion 41, 90 thus ensuring the valves 13 conforming to their seats on the surface of the outlet end of the strainer body 10.

Packing 51 is arranged around the valve stems 47 in the enlargement 46 of the borings 44-45 for preventing leakage from the inlet chamber 25 to the outlet chamber 26, the packing being retained by threaded bushings 52.

The valve stems 47 are provided near the ends thereof within the inlet chamber 25 with collars 53 extending outwardly from the valve stems, and are provided at the ends of the valve stems with heads 54 extending outwardly from the valve stems.

A wedge abutment member 55 is provided for each associated pair of valve stems 47, the associated valve stems passing through borings 56 in the wedge abutment members, and these members being located between the collars 53 and heads 54 of the valve stems 47, and rigidly connecting the associated pair of valve stems.

Each wedge abutment member is provided with lower inclined surfaces 57 and upper inclined surfaces 58 and 58^a, Figs. 1, 2 and 3, formed by cutting away the inner portion of the wedge abutment members and affording space 59 between the inclined surfaces for receiving the single or common inlet valve 12 and its wedge, both of which are later described.

The wedge abutment member 55 of one pair of associated valve stems 47 is flexibly or movably connected to the corresponding

wedge abutment member 55 of the other pair of associated valve stems 47 by links 60, each link 60 being pivotally attached at its ends to the outer side of each wedge abutment member, and pivoted at the middle of the link upon a stub shaft 61 provided by a screw-threaded bolt 62 passing through the side of the inlet valve cap or housing 23, and having a stub-end.

10 The single or common inlet valve generally denoted by 12, comprises the valve member 63 and the wedge 64.

The valve member 63 is of substantially rectangular form and has a face for covering either of the inlet ports 16, as the case may be, by engagement with the surface of the adjacent end of the strainer body 10, the face of the valve member and this surface being ground or otherwise suitably prepared to afford fluid tight connection therebetween. The valve member 63 has on two of its sides extended portions 65 having inclined surfaces 65^a for engagement with the inclined surfaces 57 of the wedge abutment member 55. The valve member 63 is provided with a rectangular inner space closed on three sides and open on the remaining side except as closed by the wedge 64.

30 The wedge 64 is suitably secured, as by the screws 67, to the valve member 63, in position closing the space 66, or the wedge may be integral with the valve member 63. The wedge 64 is provided with inclined surfaces or faces such as 68 and 68^a, for engagement with the inclined surfaces 58 and 58^a respectively of the wedge abutment members 55, the object being that the greater inclined surface 68 on the wedge 64 of the valve 12 will engage the greater inclined surface 58 on the wedge abutment member 55 thereby forcing this member outwards and by means of the connecting rods or valve stems 47 bringing the outlet valve 13 towards its seat, but not quite seating it, after which the lesser inclined surface 68^a on the inlet valve 12 will engage the lesser inclined surface 58^a on the wedge abutment member 55, thereby pulling the outlet valve 13 firmly and tightly against its seat, and simultaneously therewith forcing the single common inlet valve 12 firmly and tightly against its seat thus preventing fluid from entering strainer chamber with 55 which the ports, closed by the valves, communicate.

An interiorly threaded nut 69 is received in the space 66 of the valve member 63, the body of the nut occupying said space, and the nut being provided with outstanding flanges 70 and 71 which engage sides of the valve member 63 between the nut and valve member 63 and wedge 64, to allow the valve 12 to conform to its seat.

65 The inlet valve cap or housing 23 is pro-

vided with an extension 72 having on opposite sides of the cap or housing recesses 73 and 74 therein threaded for a portion of their depth, these recesses communicating with the outlet chamber 26 by apertures 75 through the valve cap or housing 23. An exteriorly threaded bushing 76 and a thrust collar 77 and neck 78 of the member 14 is received in the recess 73 and adjacent aperture 75, the bushing 76 having an outward flange 79 which engages the outer side of the extension 72 of the cap or housing 23, the bushing 76 having another exteriorly threaded extension 80 which provides space for receiving therein packing 81 of suitable material, retained in place by a bored nut 82, which in turn is retained by a bored cap nut 83 engaging the threaded extension 80 of the bushing 76. An exteriorly threaded bushing 84 having a neck 85 is received in the recess 74 and adjacent aperture 75.

The actuating member 14 is a rod or shaft having at one end a suitable means for operation, as the hand wheel 86, the rod or shaft having thereon for a portion of its length a screw thread 87.

The actuating member 14, when in operative position, passes through the cap nut 83, the retaining nut 82, the packing 81, the bushing 76, the rectangular nut 69, and is seated at its end in the neck 85 of the bushing 84 for turning in said neck, the screw 87 being arranged to engage the thread of the rectangular nut 69 for movement of the single common inlet valve 12 by turning of the rod or shaft by the hand wheel 86, and the valve 12 having floating connection with its valve seat.

Each strainer chamber 15 may be provided at its bottom with a suitable closable outlet, such as 88, for cleaning the strainer chamber.

In operation. The device being in operative condition, and the ports of one strainer chamber being closed by the single common inlet valve and the oppositely disposed outlet valve with which it is engaged, by revolving the single hand wheel 86, and thereby the single threaded operative member 14, the single common inlet valve 12 is actuated by the threaded portion 87 of the member 14 and forced outward away from its seat by the inclined surface 65^a on the inlet valve 12 sliding outward on the inclined surface 57 of the wedge abutment member 55, and simultaneously therewith and by the same means the outlet valve 13 with which the common inlet valve 12 is engaged by means of the wedge abutment member 55 and the connecting rods or valve stems 57, is also forced outward and away from its seat, the inlet and outlet ports of the chamber being then open. After which the common inlet valve 12 travels forward to close the other pair of inlet and outlet ports when the in-

clined surface 68 thereon engages the inclined surface 58 on the wedge abutment member 55 thereby bringing the open outlet valve connected therewith by connecting rods or valve stems 47 towards its seat but not quite seating it, after which the inclined surface 68^a engages the inclined surface 58^a thereby forcing the inlet valve 12 firmly and tightly against its seat and also simultaneously therewith pulling the outlet valve 13 with which the inlet valve is engaged firmly and tightly against its seat, the pair of inlet and outlet ports being then closed, and the clogged or fouled strainer basket in the chamber with which the closed ports communicate may then be removed and cleaned. The pivoted link 60, by the action of the inclined surfaces, completely opens the outlet port valve after it has been unseated and slightly opened, while the other outlet port valve is being closed, and holds the open outlet valve open while the other pair of inlet and outlet ports remain closed.

It will be particularly noticed that all this is accomplished by a single hand wheel, which revolves a single threaded operative member.

It is evident that, by revolving the hand wheel in a direction opposite to that in which it was first moved the operation will be again repeated.

Having thus described my invention, it should be understood that there may be modifications thereof and variations therein without departing from the spirit of the invention or exceeding the scope of the appended claims.

Having thus described my invention, I claim:

40. 1. In a strainer device, a pair of strainer chambers, an inlet chamber common to said strainer chambers, an outlet chamber common to said strainer chambers, an inlet port for each strainer chamber communicating with said common inlet chamber, an outlet port for each strainer chamber communicating with said common outlet chamber, a single common inlet valve for controlling said inlet ports alternately, a separate outlet valve for each outlet port for controlling same, and means for controlling said common inlet valve and either of said outlet valves simultaneously by a single operative member.

55. 2. In a strainer device, a pair of strainer chambers, an inlet chamber common to said strainer chambers, an outlet chamber common to said strainer chambers, an inlet port for each strainer chamber communicating with said common inlet chamber, an outlet port for each strainer chamber communicating with said common outlet chamber, a single common inlet valve for controlling said inlet ports alternately, a separate outlet valve for each outlet port for controlling

same, and means for controlling said common inlet valve and either of said outlet valves substantially simultaneously by a single threaded operative member.

3. In a strainer device, strainer chambers, an inlet chamber common to said strainer chambers, an outlet chamber common to said strainer chambers, an inlet port for each strainer chamber communicating with said common inlet chamber, an outlet port for each strainer chamber communicating with said common outlet chamber, a single inlet port valve for controlling said inlet ports alternately, a separate outlet valve for each outlet port for controlling same, means for actuating any one of said outlet port valves substantially simultaneously with and by the actuation of said single inlet valve, and means for actuating said single inlet ports valve.

4. In a strainer device, strainer chambers, an inlet chamber common to said strainer chambers, an outlet chamber common to said strainer chambers, an inlet port for each strainer chamber communicating with said common inlet chamber, an outlet port for each strainer chamber communicating with said common outlet chamber, a single inlet valve for controlling said inlet ports alternately, a separate outlet valve for each outlet port for controlling same, means for actuating any one of said outlet port valves substantially simultaneously with and by the actuation of said single inlet valve, and means for actuating said single inlet valve, said means comprising a single threaded operative member.

5. In a strainer device, a pair of strainer chambers, an inlet chamber common to said strainer chambers, an outlet chamber common to said strainer chambers, an inlet and an outlet port for each strainer chamber communicating respectively with said common inlet and outlet chambers, a single common inlet valve for controlling said inlet ports alternately, a separate outlet valve for each outlet port for controlling same, means for actuating said inlet valve and either of said outlet valves substantially simultaneously by a single operative member provided with a thread, said inlet valve being seated by the cooperating outlet valve and the cooperating outlet valve being seated by said outlet valve.

6. In a strainer device, a pair of strainer chambers, an inlet and an outlet port for each strainer chamber, a single common inlet valve adapted to control the inlet ports of both strainer chambers alternately, a separate outlet valve for each outlet port of each strainer chamber, means for substantially simultaneously closing the inlet and outlet ports communicating with either strainer chamber by causing said common inlet valve to close the inlet port of a

strainer chamber and to controllably engage the outlet valve of the corresponding and oppositely disposed outlet port for closing same, and means to cause said common inlet valve to engage said outlet valve.

7. In a strainer device, a pair of strainer chambers, an inlet and an outlet port for each strainer chamber, a single common inlet valve adapted to control the inlet ports of both strainer chambers alternately, an outlet valve for each outlet port, means for substantially simultaneously opening either pair of inlet and outlet ports of a strainer chamber, the outlet valve of the outlet port being engaged with the common inlet valve controlling the corresponding inlet port, and by disengagement of said common inlet valve from said outlet valve said outlet port controlled by said outlet valve is opened and the corresponding inlet port controlled by said common inlet valve is also opened, and means for disengaging said common inlet valve from the engaged outlet valve.

8. In a strainer device, a pair of strainer or filter chambers, each of which has an inlet for fluid thereto and an outlet for fluid therefrom; individual means for each strainer or filter chamber for opening or closing the fluid outlet therefrom; common means for opening or closing the fluid inlet of either of the strainer or filter chambers and operably connected for closing the outlet means of one of the strainer or filter chambers when the fluid inlet of such strainer or filter chamber is closed by said common means and for opening by the same operation of the common means the fluid inlet and the individual outlet means of the other strainer or filter chamber; and means for actuating the common means.

9. In a strainer device, a pair of strainer or filter chambers each of which has an inlet for fluid thereto and an outlet for fluid therefrom; individual means for each strainer or filter chamber for opening or closing the fluid outlet therefrom; common means for opening or closing the fluid inlet of either of the strainer or filter chambers and operably connected for closing the outlet means of one of the strainer or filter chambers when the fluid inlet of such strainer or filter chamber is closed by said common means, and for opening by the same operation of the common means the fluid inlet and the individual outlet means of the other strainer or filter chamber; and a single means comprising a screw for actuating the common means.

10. In a strainer device, the combination of a strainer body, comprising a pair of inlet ports and a pair of outlet ports and a pair of strainer or filter chambers, an outlet port of the pair of outlet ports being oppositely disposed to an inlet port of the pair of inlet ports; means for passage of

fluid for each strainer or filter chamber between an inlet port and the oppositely disposed outlet port; an individual valve for each outlet port; means for controlling either of the inlet ports and the outlet port oppositely disposed thereto for permitting or preventing flow of fluid through a strainer or filter chamber; and means for actuating the controlling means; said controlling means comprising a single valve for opening or closing either of the inlet ports and operatively arranged and connected for cooperation with the valve of an oppositely disposed outlet port.

11. In a strainer device, the combination of a strainer body comprising a pair of inlet ports and a pair of outlet ports and a pair of strainer or filter chambers, an outlet port of the pair of outlet ports being oppositely disposed to an inlet port of the pair of inlet ports; means for passage of fluid between the inlet ports and the oppositely disposed outlet ports; an individual valve for each outlet port; means for controlling either of the inlet ports and the outlet port oppositely disposed thereto permitting or preventing flow of fluid through a strainer or filter chamber, said means comprising a valve operatively arranged and connected for closing the valve of the outlet port of one of the strainer or filter chambers when the inlet port oppositely disposed to said outlet port is closed by said valve of the controlling means, and for opening by the same operation of the valve of the controlling means the inlet and the valve of the oppositely disposed outlet port of the other strainer or filter chamber; and means for operating the controlling means comprising a screw engaging the valve of the controlling means for actuating the valve.

12. In a strainer device, the combination of a strainer body, a pair of inlet ports and a pair of outlet ports and a pair of strainer or filter chambers, an outlet port of the pair of outlet ports being oppositely disposed to an inlet port of the pair of inlet ports; means for passage of fluid between the inlet ports and the oppositely disposed outlet ports; an individual valve for each outlet port; stems for each of said outlet valves provided with an abutment member; means for engaging the abutment member of the stem of either of said outlet valves and for engaging the inlet port of either of the strainer or filter chambers for permitting flow of fluid through one strainer or filter chamber and for preventing flow of fluid through the other strainer or filter chamber; and means for actuating said means for engagement.

13. In a strainer device, the combination of a strainer body comprising a pair of inlet ports and a pair of outlet ports and a

- pair of strainer or filter chambers, an outlet port of the pair of outlet ports being oppositely disposed to an inlet port of the pair of inlet ports; means for passage of fluid between the inlet ports and the oppositely disposed outlet ports; an individual valve for each outlet port; a stem for each of said outlet valves provided with an abutment member; a valve for engaging the abutment member of the stem of either of said outlet valves and for engaging the inlet port of either of the strainer or filter chambers for permitting the flow of fluid through one strainer or filter chamber and preventing flow of fluid through the other strainer or filter chamber; and means for actuating said valve, the valve being supported by the means for actuating the same.
14. In a strainer device, the combination of a strainer body comprising a pair of inlet ports and a pair of outlet ports and a pair of strainer or filter chambers, an outlet port of the pair of outlet ports being oppositely disposed to an inlet port of the pair of inlet ports; means for passage of fluid from the inlet ports to the oppositely disposed outlet ports; an individual valve having floating connection to its seat for each outlet port; a stem for each of said outlet valves provided with an abutment member; a valve comprising a wedge for engaging the abutment member of the stem of either of said outlet ports, and said valve being engageable with the inlet port of either of the strainer or filter chambers for permitting flow of fluid through one strainer or filter chamber and preventing flow of fluid through the other strainer or filter chamber, said valve having floating connection to its seat; and means for actuating said valve, the valve being supported by the means for actuation.
15. In a strainer device, the combination of a strainer body comprising a pair of inlet ports and a pair of outlet ports and a pair of strainer or filter chambers, an outlet port of the pair of outlet ports being oppositely disposed to an inlet port of the pair of inlet ports; means for passage of fluid from the inlet ports to the oppositely disposed outlet ports; an individual valve for each outlet port; a stem for each of said outlet valves provided with an abutment member; means for movably connecting the abutment members; means for engaging the abutment member of the stem of either of said inlet valves and for engaging the inlet port of either of the strainer or filter chambers for permitting flow of fluid through one strainer or filter chamber and preventing flow of fluid through the other strainer or filter chamber; and means for actuating said means for engagement.
16. In a strainer device, the combination of a strainer body comprising a pair of inlet
- ports and a pair of outlet ports and a pair of strainer chambers, an outlet port of the pair of outlet ports being oppositely disposed to an inlet port of the pair of inlet ports; means for passage of fluid from the inlet ports to the oppositely disposed outlet ports; an individual valve having floating connection to its seat for each outlet port; a stem for each of said outlet valves provided with an abutment member thereon; links for movably connecting the abutment members; a valve having floating connection to its seat and comprising a wedge for engaging the abutment member of the stem of either of said outlet valves, and said valve being engageable with the inlet port of either of the strainer chambers for permitting flow of fluid through one strainer chamber and preventing flow of fluid through the other strainer chamber; a shaft for supporting said valve and provided with a screw engaging said valve for actuating the valve; and means for rotating said shaft.
17. In a strainer device, the combination of a strainer body comprising a pair of outlet ports; an individual valve for each outlet port; a stem for each of said outlet valves provided with an abutment member; means for movably connecting the abutment members; means engageable with the abutment member of the stem of either of said outlet valves for moving the abutment member to close the outlet port cooperating with said outlet valve; said means for movable connection, when the abutment member is engaged by said engageable means, moving the abutment member of the stem of the other of said outlet valves to actuate the stem of such outlet valve to further open the outlet port communicating with said outlet valve; and means for actuating the engageable means.
18. In a strainer device, the combination of a strainer body having a pair of inlet ports and a pair of outlet ports, an outlet port of the pair of outlet ports being oppositely disposed to an inlet port of the pair of inlet ports; an individual valve for each outlet port; a stem for each of said outlet valves provided with an abutment member; links for movably connecting the abutment members; a valve engageable with either of said inlet ports and engageable with the abutment member of the stem of either of the outlet valves, and movable for engagement with the abutment member of the stem of either of said outlet valves to actuate the stem of such outlet valve to close the outlet cooperating with said outlet valve, and said engageable valve closing the inlet port oppositely disposed to the outlet port so closed, and said links, when the abutment member is engaged by said valve, moving the abutment member of the stem of the other of said outlet valves to actuate the

stem to further open the outlet port communicating with said outlet valves, the last mentioned outlet port having been slightly opened, and the oppositely disposed inlet port thereof having been completely opened by prior movement of said engageable valve; and a single means for actuating the engageable valve.

19. In a strainer device, a pair of strainer chambers, an inlet chamber common to said strainer chambers, an inlet port and an outlet port for each strainer chamber the inlet ports communicating with the common inlet chamber, a separate outlet valve for each outlet port, a common valve for closing the inlet port of either strainer chamber and substantially simultaneously opening the inlet port of the other strainer chamber by actuation of the common valve, means appurtenant to the valves of the outlet ports operatively connected to said common valve, and means for actuating the common inlet valve; said appurtenant means, when the common inlet valve is actuated for closing the inlet port of either strainer chamber, closing the valve of the outlet port cooperating with said inlet port closed by actuation of the common inlet valve, and substantially simultaneously opening the valve of the outlet port cooperating with said inlet port opened by said actuation of the common inlet valve.

20. In a strainer device, a pair of strainer chambers, an inlet chamber common to said strainer chambers, an inlet port and an outlet port communicating with the common inlet chamber, a separate outlet valve for each outlet port, a common valve for closing the inlet port of either strainer chamber and substantially simultaneously opening the inlet port of the other strainer chamber by actuation of the common inlet valve, means appurtenant to the valves of the outlet ports engageable with the common inlet valve, and means for actuating the common inlet valve; said appurtenant means, when the common inlet valve is actuated for closing the valve of the inlet port of either strainer chamber, engaging the common inlet valve for closing the valve of the outlet port cooperating with said inlet port closed by actuation of the common inlet valve, and substantially simultaneously opening the valve of the outlet port cooper-

ating with said inlet port opened by said actuation of the common inlet valve. 55

21. In a strainer device, a pair of strainer chambers, an inlet chamber common to said strainer chambers, an inlet port and an outlet port for each strainer chamber, the inlet ports communicating with the common inlet chamber, a stemmed outlet valve for each outlet port, a common valve for closing the inlet port of either strainer chamber and substantially simultaneously opening the inlet port of the other strainer chamber by actuation of the common inlet valve, means on the stems of the outlet valves cooperating with the common inlet valve, and means for actuating the common inlet valve; said 70 means on the stems of the outlet valves, when the common valve is actuated for closing the inlet port of either strainer chamber, closing the valve of the outlet port cooperating with said inlet port closed by actuation 75 of the common inlet valve, and substantially simultaneously opening the valve of the outlet port cooperating with said inlet port opened by said actuation of the common inlet valve. 80

22. In a strainer or filter device, the combination of a body having a pair of inlet ports and a pair of outlet ports, an outlet port of the pair of outlet ports oppositely disposed to an inlet port of the pair of inlet ports; an individual valve for each outlet port; a stem for each of said outlet valves provided with an abutment member; means for preventing leakage past said stems; means for movably connecting said 90 outlet valves; a valve engageable with either of said inlet ports and engageable with the abutment member of the stem of either of the outlet valves, and movable for engagement with the abutment member of the stem 95 of either of said outlet valves to actuate the stem of such outlet valve to close the outlet cooperating with said outlet valve, and said engageable valve closing the inlet port oppositely disposed to the outlet port so closed, and said means movably connecting the outlet valves, when the abutment member is engaged by said valve, moving the other outlet valve to open the outlet port oppositely disposed to the inlet port opened by the 100 movement of said valve. 105

LOUIS J. GROVES.
